UNITED STATES PATENT OFFICE.

EDWARD L. DELANY, OF BROOKLYN, NEW YORK, ASSIGNOR TO DELANY REALTY CORPORATION, OF BROOKLYN, NEW YORK.

FLUSH-TANK-OPERATING LEVER.

Application filed September 29, 1925. Serial No. 59,369.

My invention relates to improvements in flush tank operating levers.

The object of my invention is to provide a flush tank operating lever which can be readily attached and removed from the flush tank and in which a good strong fulcrum for the operating handle is obtained, and at the same time providing means whereby the knob is permanently attached to the lever and the same inserted and removed from the outside of the tank.

Another object of my invention is to provide a flush tank operating lever of this character in which the operating lever may be readily removed from the tank and the flush valve carrying lever also readily removed and the fulcrum of the operating lever serving as means for attaching the flush valve lever to the tank, whereby any of the parts can be replaced when worn or broken.

A further object of my invention is to provide a simple, cheap and effective flush tank operating lever which is strong and durable and having certain details of structure and combination of parts hereinafter more fully set forth.

In the accompanying drawings:—

Figure 1 is a horizontal sectional view through the front wall of the flush tank showing my improved operating lever applied thereto.

Figure 2 is a vertical transverse sectional view taken on the line 2—2 Figure 1.

Referring now to the drawings, 1 represents the flush tank which is provided with an opening 2, preferably of a rectangular form through which a corresponding shaped sleeve 3 passes. This sleeve is provided at its outer end with an annular flange 4 which engages the outer face of the flush tank, 1, to limit the inward movement of the sleeve. The corners of the sleeve are rounded off in beyond the wall of the flush tank 1, and are threaded as indicated at 5, and upon which is screwed the nut 6, which engages the inner face of the wall of the tank, and tightly locks the same to the tank 1. The sleeve 3 is provided with a rectangular opening 7 therethrough, and through which extends the operating lever 8, which extends inwardly a considerable distance beyond the inner end of the sleeve. This lever is provided, intermediate its ends, with an oblong enlarged portion 9, having a transverse

opening 10 therethrough, and through which passes the pivot 11, whereby the lever is pivotally mounted within the sleeve and has a limited movement. The enlarged portion 9 being oblong, it will be seen that there is a considerable space 12 left above and below the same so that the lever can have the desired movement to allow for the proper throw of the flush valve carrying lever as will be hereinafter more fully described. Surrounding the outer end of the sleeve 3 is a collar 13 which is of a rectangular form so that it will tightly fit the walls of the sleeve and is provided with the oppositely arranged openings 14 and 15, arranged opposite the opening in the sleeve and through which the pivot 11 passes. The opening 15 is threaded to receive the threaded end 16 of the pivot 11, whereby the pivot is locked in the position shown in Figure 1 of the drawings. The collar 13 is provided with a laterally extending ear 16' to which is rigidly attached the laterally extending pivot 17. The float carrying lever 18 has its end formed into a loop as indicated at 19 and provided with the oppositely arranged openings 20 and 21 through which the pivot 17 passes, whereby the valve carrying lever 18 can freely rock thereon and is held against lateral movement. A cotter pin 22 holds the lever 18 on the pivot 17 against longitudinal movement thereon. The extension 23 of the lever 3 passes through an opening 24 in the flush valve lever 18, whereby the rocking of the lever 3 on the pivot 11 within the sleeve causes the flush valve operating lever 18 to rock on the pivot 17, and the valve is raised from its seat, all of which is well understood and needs no further description.

The extension 23 of the lever 3 is provided with an opening through which the cotter pin 25 extends, which will to a certain degree prevent any lateral or twisting movement of the lever 18 on the pivot 17.

The lever 8 has its inner end roughened as indicated at 25 whereby the knob 26 is permanently attached thereto by cement 27, or in any desired manner. In assembling the device, the sleeve is first passed through the opening in the flush tank and the nut 6 screwed thereon to tightly lock it to the flush tank. The collar 13 is then placed upon the inner end of the sleeve 3 and the operating lever 8 is inserted through the

sleeve from the outside until the opening 10 registers with the openings in the sleeve. The openings 14 and 15 carried by the collar are moved to register with the openings in 5 the sleeve, and the pivot 11 is then passed through the opening in the collar, the sleeve and the lever, and screwed into the opening 15 in the collar. It will be understood that the flush valve operating lever 18 had been 10 previously assembled on the pivot 17 as hereinbefore described. By this structure it will be seen that a broad strong pivotal connection is made between the operating lever 8 and the sleeve so that the same will 15 not readily wear or break, due to the sudden strain placed thereon, and that the sleeve 3 limits the movement of the lever 8 in its upward and downward movement.

Having thus fully described my invention what I claim is:

1. A flush tank operating lever comprising a tubular member, an operating lever passing through the tubular member, a removable member carried by the tubular 25 member, a flush valve operating lever pivotally carried by the removable member, and a pivot passing through the tubular member and forming a fulcrum for the operating lever, and holding the removable 30 member on the tubular member.

2. A flush valve operating lever comprising a sleeve, means for fastening the same to the flush tank, a collar carried by the inner end of the sleeve, a flush valve operating lever pivotally mounted on the collar, an operating lever passing through the sleeve, and operating the flush valve carrying lever, and a pivot passing through the collar, the sleeve and the operating lever 40 for locking the collar to the sleeve and pivotally mounting the lever within the sleeve.

3. A flush valve operating lever comprising a sleeve adapted to be locked to the flush tank, a flush valve carrying lever removably attached to the inner end of the sleeve, an operating lever passing through the sleeve and operatively connected to the flush valve carrying lever, and a pivot passing 45 through the sleeve and the operating lever, and adapted to lock the flush valve operating lever to the sleeve.

4. A flush valve operating lever comprising a sleeve, means for removably connecting the sleeve to the tank, a collar mounted on the inner end of the sleeve, a flush valve carrying lever pivotally mounted on the collar, an operating lever passing through the sleeve and operatively connected to the flush-valve carrying lever, and a pivot passing 55 through the collar, the sleeve and the operating lever, whereby the lever is pivotally mounted within the sleeve and the collar held on the sleeve.

5. A flush valve operating lever comprising

ing a sleeve adapted to be secured to the flush tank, a collar surrounding the inner end of the sleeve and having a lateral extension, a pivot rigidly carried by said extension, a flush valve carrying lever pivotally mounted upon said pivot, an operating lever passing through the sleeve and through a slot in the flush valve carrying lever, and a pivot passing through the collar, the sleeve and the lever for pivotally mounting the lever within the sleeve and securely holding the collar on the sleeve.

6. A flush valve operating lever comprising a tubular member adapted to be secured to the flush tank, a removable member carried by the tubular member, a flush valve operating lever pivotally mounted upon the removable member, an operating lever passing through the tubular member into an opening in the flush valve operating lever 80 and having an enlarged bearing portion forming a fulcrum therefor and a pivot locking the removable member to the tubular member.

7. A flush valve operating lever comprising a sleeve adapted to be secured to the flush tank, and having a rectangular opening therethrough, an operating lever having a knob permanently secured to its outer end and passing through the sleeve and having a rectangular enlarged portion intermediate its ends within the sleeve, and a pivot passing through the sleeve and the enlarged rectangular portion of the lever, whereby the lever has a large bearing surface on the pivot and a limited movement within the sleeve.

8. A flush valve operating lever comprising a sleeve having means for attaching it to the flush tank, a collar mounted on the inner end of the sleeve and having a pivot rigidly carried thereby, a flush valve operating lever having a looped portion through which the pivot passes, an operating lever passing through the sleeve and operatively connected to the flush valve operating lever, and having a knob permanently attached thereto and having an enlarged portion intermediate its ends, and a pivot passing through the collar, the sleeve and the enlarged portion of the operating lever.

9. A flush valve operating lever comprising a rectangular sleeve having its corners rounded and threaded, a nut on the threaded portion and adapted to clamp the sleeve to the tank, a collar removably mounted on the inner end of the sleeve, and having a lateral extension, a pivot rigidly carried by said extension, a flush valve operating lever having a looped portion through which the pivot passes, an operating lever having a knob permanently connected to the outer end and having its inner end passing through the sleeve, and having its inner end passing loosely through an opening in

the flush valve operating lever, and having an enlarged portion within the sleeve, and a pivot passing through a collar, the sleeve and the enlarged portion of the operating lever, whereby the lever has a broad pivoted connection within the sleeve, and the collar is secured on the sleeve.

10. A flush valve operating lever comprising a tubular member, a vertically movable operating lever passing through the tubular member, a removable member on the tubular member, a valve lever pivoted on the removable member, and a removable pivot passing through the tubular member and the operating lever and securing the removable member thereon.

11. A flush valve operating lever comprising a tubular member adapted to be secured to the tank, a removable sleeve on the tubular member, a valve lever pivoted to the sleeve, an operating lever passing through the tubular member, and having a loose connection with the valve lever, and

a pivot passing through the sleeve, the tubular member and the operating lever for securing the sleeve on the tubular member and pivotally mounting the operating lever within the tubular member.

12. A flush valve operating lever comprising a tubular member, a vertically movable operating lever passing through the tubular member, a removable member on the tubular member, a valve lever pivoted on the removable member, a removable pivot passing through the tubular member and the operating lever and securing the removable member thereon, and forming a fulcrum for the operating lever, whereby the removable pivot can be removed and the removable member removed from the tubular member, and the pivot placed in position to hold the operating lever in position during shipping.

In testimony whereof, I have signed this specification.

EDWARD L. DELANY.
